CLAIM

[21] Appl. No.: **14,805**

The ornamental design for an electromagnetic current meter, as shown and described.

[22] Filed: **Sep. 22, 1993**

DESCRIPTION**Foreign Application Priority Data**

Mar. 25, 1993 [JP] Japan 5-8526

FIG. 1 is a front view showing my new design for an electromagnetic current meter;
FIG. 2 is a top view thereof;
FIG. 3 is a bottom view thereof;
FIG. 4 is a right side elevational view thereof, the left side elevational view being a mirror image;
FIG. 5 is a rear view thereof; and,
FIG. 6 is a perspective view thereof.
